OTHER PUBLICATIONS

U.S. Appl. No. 29/511,482, Nicolette et al., "Golf Club Head," filed
Dec. 11, 2014.

(Continued)

Primary Examiner — Mitchell Siegel**CLAIM**The ornamental design for a golf club head, as shown and
described.**DESCRIPTION**

FIG. 1 is a top perspective view of a golf club head;
FIG. 2 is a bottom perspective view of the golf club head of
FIG. 1;
FIG. 3 is a front elevational view of the golf club head of FIG.
1;
FIG. 4 is a rear elevational view of the golf club head of FIG.
1;
FIG. 5 is a top view of the golf club head of FIG. 1;
FIG. 6 is a bottom view of the golf club head of FIG. 1;
FIG. 7 is a left side view of the golf club head of FIG. 1; and,
FIG. 8 is a right side view of the golf club head of FIG. 1.
The broken lines are included for the purpose of illustration
only. None of the broken lines forms part of the claimed
design.
